153,521

DESIGN FOR A COVER OF A CONTAINER OR THE LIKE

Elizabeth N. Graham, New York, N. Y., assignor to Elizabeth Arden Sales Corporation, New York, N. Y., a corporation of Delaware

Application July 3, 1946, Serial No. 131,311

Term of patent 14 years

(Cl. D58—12)

To all whom it may concern:

Be it known that I, Elizabeth N. Graham, a citizen of the United States and a resident of the city, county, and State of New York, have invented a new, original, and ornamental Design for Cover of a Container or the like, of which the following is a specification, reference being had to the accompanying drawing, forming a part thereof, and wherein:

Fig. 1 is a top plan view of a cover of a container showing my design; and

Fig. 2 is a front elevational view thereof.

The characteristic features of my design reside in the combination on the cover of a container disclosed of the specific crab and fish ornamentation shown thereon.

I claim:

The ornamental design for a cover of a container or the like, substantially as shown and described.

ELIZABETH N. GRAHAM.
